DISPENSING CARTON

Frank A. Marx, Bridgetown, Ohio, assignor to
The Richardson Taylor-Globe Corporation,
Cincinnati, Ohio, a corporation of Ohio

Application May 14, 1943, Serial No. 486,995

2 Claims. (Cl. 229—11)

This invention relates to two-piece cartons comprising an outer covering member or sleeve and an inner member providing the container portion. The latter has a dispensing aperture adjacent one end which is exposed for use by pushing the inner member outwardly of the sleeve to the required extent.

An object of the invention is to provide devices of this kind which obviate certain gluing steps heretofore usually applied by the packer after receiving the cartons, in the flat condition, from the manufacturer.

Another object is to provide cartons of the character described adapted to preclude leakage of the contents, especially of powdered material.

Another object is to provide such cartons having a novel construction of the end wall and associated parts.

Another object is to provide cartons of this character adapted for simple and efficient manufacture and ease of assembly.

These and other objects are attained by the means described herein and illustrated in the accompanying drawings in which:

Fig. 1 is a perspective view of one form of the invention in operative dispensing position.

Fig. 2 is a cross-sectional view on the line 2—2 of Fig. 1.

Fig. 3 is a perspective view of the carton with one end completely opened as for the purpose of filling.

Fig. 4 is a plan view of the blank out of which the inner or container portion of the carton is formed.

Fig. 5 is a plan view on a reduced scale of the blank out of which the sleeve of the carton is formed.

Fig. 6 is a perspective view of a second form of the carton of this invention in operative dispensing position.

Fig. 7 is a cross-sectional view taken on line 7—7 of Fig. 6.

Fig. 8 is a perspective view of the carton with one end completely open for the purpose of filling.

Fig. 9 is a plan view of the blank out of which the inner or container portion of this second form of carton is constructed.

Fig. 10 is a plan view on a reduced scale of the sleeve portion of the carton.

Fig. 11 is a perspective view of a third form of carton of this invention shown in dispensing position.

Fig. 12 is a cross-sectional view taken on line 12—12 of Fig. 11.

Fig. 13 is a cross-sectional view on line 13—13 of Fig. 11.

Fig. 14 is a perspective view of the inner or body portions of this form of the carton, with one of the end sections disposed above the body portion preparatory to positioning thereof.

Fig. 15 is a plan view of the blank for forming the body portion of the inner member.

Fig. 16 is a plan view in flat position, of the end member of this form of the carton.

As already indicated, the present invention is particularly useful for eliminating gluing operations on the part of the packer. Heretofore it has usually been necessary for the packer, utilizing cardboard cartons, to apply glue to certain of the parts of the cartons before erecting them for the filling and closing operations. Such gluing not only required considerable time and skill, but likewise the installation and maintenance of machinery for that purpose. The cartons of the present invention can be erected in a fraction of time into fully operative conditions without any gluing whatever. In addition to this, the various other advantages of simplicity of construction and use will be apparent in the course of the following description.

With reference to the drawings, in Fig. 1, the carton comprises a sleeve or cover 18 formed of a rectangular sheet of material such as seen in Fig. 5, provided with the score lines 19 upon which the blank is folded, and with the glue section 20 for securing this section to the opposite end portion of the blank as seen at 21 in Fig. 2.

The inner or container portion of the carton is formed of a blank cut and scored to provide the body portion 22 made up of sections 23, 24, 25, and 26, adapted to be folded on the score lines 27 to provide a body of a cross-section similar to, but somewhat smaller than the cross-sectional outline of the sleeve 18. The said body 22 is held together by means of the glue strip 28, attached as at 29, Fig. 2, to the opposite extremity of the body.

One of the sections of the body, such as section 24, has hingedly connected to one end an end closure 30, which is provided with lateral flaps 31, 32, and 33.

Similarly the opposite end of the section 24 may have attached thereto the end closure 34 provided with lateral flaps 35, 36, and 37.

The blank so formed is erected into filling position by first squaring up the body 22. Thereafter the end closure 34, forming the bottom, is moved into closing position and the flaps 35, 36, and 37, folded against the sides of the body. These bot-

tom portions of the body are now inserted into the sleeve 18 as seen in Fig. 3, in which position the carton is filled through the open top.

After filling, the top end 30 and flaps 31, 32, and 33, are folded downwardly and these portions of the body pushed into the sleeve 18, whereby the carton is completely closed.

It will be noted that the section 25 of the body and the associated flap 33 of the top, are provided with registering perforations 38 and 39, respectively, through which the contents of the carton may be dispensed. This is, of course, accomplished by pushing the container portion of the carton outwardly of the sleeve and exposing the dispensing aperture, such outward projection being stopped short of the inner ends of the flaps 31, 32, and 33, so that the latter are not released from their closed position as held by the sleeve. In the carton as herein shown, the flaps of the top and bottom of the body are of such length as to meet edgewise in their operative positions, whereby the wall thickness of the carton is increased and the carton thereby strengthened.

In Figs. 6 through 10, a second form of the invention is illustrated. Herein the sleeve 40 is formed of a blank (Fig. 10) similar to the one previously described, which in the completed condition provides a sleeve of rectangular cross-section.

The inner or container portion of this carton is formed of the blank seen in Fig. 9, in which the section 41 forms the outer back of the body. This has connected thereto at one side, the side section 42. The latter in turn has the inner front section 43 attached thereto along score line 44 and the section 45 is attached to the section 43 along the score line 46. The section 47 forms the inner back wall of the body and is connected to the adjacent section along the score line 48. A glue strip 49 is attached to the section 47. In Fig. 9, the glue is on the underside of the strip 49.

To the right of the outer back section 41 of the body (Fig. 9), are shown the three additional sections 50, 51 and 52, the latter having a glue strip 53 connected therewith, the glue in this instance being shown on the upper side of the blank. Section 50 is shorter than the various body sections shown on the lefthand side of Fig. 9, while the sections 51 and 52 are again shorter than the section 50 at the top.

The back section 41 likewise has at one end upper closure 54 to which are connected the lateral flaps 55, 56, and 57, the latter being shorter than the other two for a purpose to be described. Finally, the back section 41 of the body has a bottom closure 58 formed with lateral flaps 59, 60, and 61, which may all be of the same length.

The body of the carton is erected into operative position by first folding the blank as seen in Fig. 9, along the score line 48, which places the glue strip 49 in overlying position upon the section 43, with the glue disposed upwardly. The blank is now further folded along the line 44 whereby the glue face of strip 49 is brought down on the section 42 and thereto secured by the glue.

The section 50 is now turned over against the section 45, which brings the shorter section 51 against the section 47 while the glue strip 53 comes into contact and is secured to the outer face of the section 42.

It will be understood that both the sleeve 40 and the inner or body section just described, are shipped flat to the user or packer. The latter, upon use of the carton, simply erects the con-

tainer portion of the carton into the squared position seen in Figs. 7 and 8 with the bottom closure 58 and the side flaps 59, 60, and 61, in position against the adjacent bottom portions of the body, at which time the inner edges of said flaps are substantially in abutment against the bottom edges of the sections 50, 51, and 52.

These bottom parts held in the position seen in Fig. 8, are now inserted into the sleeve 40, the top closure 54 and its flaps being left open to permit filling of the carton. After this has been accomplished the said top closure 54 and flaps 55, 56, and 57 are folded down against the adjacent portions of the body.

It should be here explained that the section 45 of the body is provided with dispensing apertures 62 disposed above the section 50 of the body. These apertures are effectively closed by the short top flap 57 when the sleeve 40 is pushed over the top portions of the filled carton.

When it is desired to dispense from the carton, the body or container portion is pushed outwardly as seen in Fig. 6 to an extent sufficient to release the short flap 57 and thereby expose the dispensing apertures 62.

In the closed position, the lower edge of the short flap 57 substantially abuts the top edge of the section 50 of the body while the lower edges of the other two flaps 55 and 56 similarly meet the top edges of the sections 51 and 52, respectively.

A third form of the invention is illustrated in Figs. 11 through 16, wherein the sleeve 63 is formed of a blank 64 generally similar to those previously described, except that in this instance the sleeve is of hexagonal outline, having its edges connected together as at 630.

The container portion comprises three sections. The main section is the body 65 which is substantially identical with the sleeve 63, although of somewhat smaller cross-sectional outline. It is provided adjacent one end with a dispensing aperture 66. The glue flange is seen at 650.

The body is embraced by end members, each of which comprises the end closure 67 having the lateral flaps 68 connected therewith. The end closures 67 are of an outline similar to the cross-sectional shape of the body 65, that is to say, in this instance, the end closures are hexagonal and therefore have six lateral flaps 68. These lie against the respective outer faces of the body 65 and are held in this position by the sleeve 63 when the latter is slipped over the assembled container portion. It will be seen that one of the flaps 68 is provided with an aperture 69 adapted to register with the aperture 66 of the body, the dispensing port so formed being adapted to be exposed for use by pushing the container or inner portion of the carton outwardly of the sleeve to the required extent as seen in Figs. 11 and 13. The lateral flaps 68 of the two end members of the body are preferably of such length as to substantially meet when in operative position so that another thickness is added to the walls of the carton for strengthening the latter.

In all of the forms of the cartons described, the dispensing ports or apertures, may, prior to actual use of the carton, remain covered or filled by the usual knockout tabs, which, when it is desired to dispense the contents of the cartons, are simply pushed inwardly.

What is claimed is:

1. A dispensing carton of flexible sheet material and comprising an outer sleeve and a container portion slidably therein, the container portion

consisting of a one-piece blank foldable to provide a body similar in cross-sectional outline to said sleeve, and end walls each formed with lateral flaps held against the body by said sleeve, one of the flaps and the body portion therebelow being provided with a dispensing aperture normally covered by said sleeve and exposed by pushing the body outwardly of the sleeve to the required extent.

2. A dispensing carton of flexible sheet material and comprising an outer sleeve and a container

portion slidable therein, the container portion comprising a body similar in cross-sectional outline to the sleeve, and an end closure formed with lateral flaps held against the body by the sleeve for retaining the end closure in place, the body and one of said flaps being provided with a registering, dispensing aperture exposed for use by pushing the body outwardly of the sleeve to the required extent.
